UNITED STATES PATENT OFFICE.

LOUIS FORT, OF JERSEY CITY, NEW JERSEY.

WEATHERPROOF OUTLET.

1,284,291.

Specification of Letters Patent. Patented Nov. 12, 1918.

Application filed March 29, 1915. Serial No. 17,639.

To all whom it may concern:

Be it known that I, LOUIS FORT, a citizen of the United States, and a resident of Jersey City, in the county of Hudson and

5 State of New Jersey, have invented certain new and useful Improvements in Weather-proof Outlets, of which the following is a full, clear, and exact description, whereby any one skilled in the art may make and use 10 the same.

The invention relates to what might be termed a wire and a weather-proof outlet and is designed for use in interior and exposed locations to cover and protect the ends 15 of conduits and forms a convenient insulated bushing to lead terminal wires from a conduit.

The object of the invention is to provide a simple, inexpensive and convenient form 20 of device which is applicable to conduits, whether they are arranged horizontally or vertically.

A further object is to provide a single structure which will meet all requirements 25 by a simple reversal of the position of the base and clamping devices, providing for any desired number of outlets.

A further object is to provide a device 30 which, when applied, will close and will seal the end of the conduit protecting it from the weather and which may be opened for various leads as it is designed to take them out through the cap.

Referring to the drawings:

35 Figure 1 is a vertical sectional view through the device as applied to a horizontally disposed conduit.

Fig. 2 is a similar view showing the device applied to a vertically disposed conduit.

40 Fig. 3 is a perspective view of the base-part and clamping members.

Fig. 4 is a perspective view of the combined cap and casing which fits upon the base-part of Fig. 3.

45 Fig. 5 is a detail sectional view of the insulating block which closes the outlet of the casing.

Fig. 6 is a cross sectional view through the device in a form for interior wiring 50 upon a horizontal conduit.

Fig. 7 is a similar view illustrating the parts arranged on a vertically disposed conduit with the outlet for the wires at the top.

Fig. 8 is an end view showing the same 55 position of parts as Fig. 7, with the cover arranged for leading the wires out at right angles to the conduit.

Fig. 9 is a view similar to Fig. 6 employing the device and horizontal conduit with the cover having its outlet at right angles 60 to the conduit.

Fig. 10 is a view in elevation of the device as illustrated in Fig. 8.

Fig. 11 is a longitudinal section through the device on the line 11—11 of Fig. 6. 65

In modern practice, practically all wires for electrical purposes where used about buildings are carried in conduits usually of pipe form.

Where service conduits are employed extending from line conductors to buildings, it is important that the conduits of the buildings where the wires enter be protected against rain, sleet and other weather conditions. The invention herein described 70 contemplates an adjustable device which may have a universal application, inasmuch as the same device may be applied to conduits, whether they extend horizontally through the wires or vertically thereof. The 75 device completely covers the end of the conduit, may be securely fastened with reference thereto and gives a perfect shield.

In the accompanying drawings, the numeral 1 denotes the line of the wall through 80 which extends the conduit 2. As illustrated in Fig. 1, the conduit 2 extends horizontally through the wall. In Fig. 2, the conduit extends vertically of the wall.

Fitting over the projecting end of the 85 conduit 2, there is a base and clamping member 3. This base member has walls 4, 5 of substantially equal widths joined at right angles to each other. The wall 4 has a perforation 6 which fits over the end of the 90 conduit 2 and interiorly arranged within the base-part is a clamping block 7 having a semi-cylindrical seat 8 within which the pipe rests.

On either side of the semi-cylindrical seat 100 are threaded openings 9 by which a clamp member 10 is secured about the end of the pipe, clamping the base thereto. This clamp member 10 has a semi-circular opening and around its edge is a rounded bead 105 11 which gives a smooth surface against which there is no liability of the wires 12 abrading. The base 4 is provided with end members 13, 14 with screw-threaded openings 15 by which the cap or casing member 110 may be secured thereto.

Between the end members 13, 14 and the ends of the side walls 4 and 5 are arranged seats 16, 17, which are in continuation re-

spectively of the walls 4 and 5. The outer edges are preferably beveled to provide a water shed and the edges of the walls 4 and 5 are beveled as at 18, 19.

5 It is apparent that the opening 6 may be placed over the end of the conduit 2 and with the wall 4 resting against the wall or other support. The opening 6 may be placed over a vertical conduit, whereupon 10 the wall 5 will rest against the wall of the building or other support. Whether the seat is placed over a horizontal conduit or a vertical conduit, the seats 16, 17, will receive the cap member 20. This cap member 15 has end walls 21, 22, which extend over the extreme ends of the walls of the base which provide the seats 16, 17. They are preferably formed with thickened portions 23, which will engage and rest upon the seats 20 16, 17.

The bottom and back of the casing are open so that the rear edge 24 which is beveled inwardly will fit either the bevel 18 or the bevel 19 of the walls 4 and 5 of the base 25 when the end walls rest upon the seats 16, 17. The beveled edge 25 of the opening through the bottom will register with the beveled edge 19 when the edge 24 is in registering position with the edge 18.

30 This cap member is secured to the base by screws projecting through the ends thereof and engaging the threaded openings 15.

The top of the cap is rounded as at 26 and 35 has an extended hood portion 27 projecting downward therefrom. Angularly disposed within the hood section 27, there is a seat 28 provided with screw-threaded lugs 29 by which an insulating plate 30 may be set 40 cured to cover the hood opening 31.

This insulating block is of peculiar form in that it is provided with a series of partially formed tubular openings 32 extending from both sides of the plate and providing 45 convex buttons 33. These buttons are a part of the plate but as the edges which join the sides of the tubular opening are comparatively thin owing to the opposed convex formation, they may be driven out with 50 out liability of fracturing the plate and without leaving irregular protrusions in the cylindrical openings. They need be just sufficiently thick to form a closure for the opening through the hood and are arranged 55 in sufficient numbers to serve for any desired system of wiring.

As illustrated, the plate contains three outlet openings and this plate, obviously, may be used either for a two or three wire 60 system.

In practice, the base is clamped to the end of the conduit and the cap is applied thereto. When it is desired to connect in the line circuits, the wires are passed 65 through the opening 32 of the insulating

plate, the button 33 being, of course, "knocked out." The cap member 21 is then placed in position and secured to the base member 3.

Of course, the wires 12 are dipped below 70 the hood of the casing and secured in any of the usual manners of wiring. Ordinarily, they are looped down sufficiently to provide a drip which will carry away water or moisture from the hood.

In Figs. 6 to 10 of the drawings, there is illustrated a device having the same elements as heretofore described though of a form specially adapted for use on interior wiring. For this purpose the extended hood 80

is not so essential as in exterior work and thus, the removable casing section is modified as to form. This casing section forms a complete and tight closure when placed upon the base and is universal in its application 85

so that leads may be taken from a horizontal conduit either in line with the conduit or at right angles thereto and similarly, the leads may be taken from a vertical conduit in either a horizontal or vertical 90

direction by varying the position of the base-part and casing member. In these figures, the base-part 34 is of the same form as heretofore described. The inclosing casing 35 has two sides 36, 37 substantially 95

equal in size and these are joined by end walls 38, 39 which rest upon the seats 40, 41 respectively. These seats are formed by extending the side walls 42, 43 of the base 100

member slightly beyond the ends 44, 45 which connect the side-walls 42, 43. The edges of the walls 42, 43 are beveled as heretofore described and the edges of the walls of the inclosing casing are similarly beveled between the ends 38, 39. This provides 105 a close tight fit and permits the base-part and casing part to be reversed in position as may be desired.

The casing member will fit the base-member when it is used on the horizontal casing 110 as illustrated in Figs. 6 and 9 so that the wires may be led out horizontally through the casing member or vertically therethrough.

The casing member will equally well fit 115 upon the base-member when the latter is employed upon a vertically disposed conduit as illustrated in Figs. 7 and 8 and obviously, the casing can be applied in two different positions upon the base so that the wires from the vertical conduit can be led directly 120 up to the top of the casing or they may be led out through the side or the front thereof.

One wall as 37 of the casing has a substantially rectangular recess 46 within 125 which is seated and secured by suitable screws 47 a block of insulating material 48 similar in form and construction to that illustrated in Fig. 5. This provides for thoroughly insulating the wires where they 130

pass through the walls of the casing. It also provides for giving a complete closure to the interior as the plate is imperforate until used and when in use, the wires fill the 5 openings through the insulating plate.

Within the base-section and in line with the perforation 49 which is arranged to receive the conduit is a split clamp having a base section 50 and a top 51. These parts 10 are clamped together by suitable screws. The inner edge of the clamp members is rounded and of a diameter substantially equal to the inner diameter of the conduit which, in practice abuts against the shoulders as formed. The upper clamp member has dependent guide arms 52 which straddle the central portion 53 of the lower clamp member.

The cap is secured to the base section in 20 any suitable manner as by screws 54.

It is quite obvious that this form of the device for interior wiring shown in Figs. 6 to 10 is identical with that of Figs. 1 to 5 in its elemental combination, but that its 25 interior form is modified to suit the differences in condition. The device for interior purposes is much neater and compact than for exterior wiring and obviously, does not require the extended hood form of casing to 30 provide water drips, etc. Of course, the precise form of the device as illustrated for interior wiring need not be strictly adhered to in its lines of design and the form may be modified to suit the exigencies of any particular case so long as the base is applicable to vertically or horizontally disposed conduits and the inclosing casing is interchangeable on the base in either of said uses and arranged so that it will fit and inclose 35 the base-part and conduit, providing for wire-leads either at right angles to or in continuation of the conduit.

Obviously, the device herein described is applicable to conduits in any position and 45 the single structure serves as a perfect closure and cap to protect the conduit and its wires from the weather. It is equally obvious that the device provides a perfect closure completely incasing the conduit, 50 whether a one, two or three wire system is employed and that there is a complete closure prior to passing the wires through the hood part and insulating plate, as well as after the wires have been run.

55 What I claim as my invention and desire to secure by Letters Patent is:

1. A weather-proof outlet, comprising a base of rectangular form having two side walls joined at right angles to each other,

one of said walls having a centrally arranged 60 perforation to receive a conduit, with the base part arranged either upon a vertically or horizontally disposed conduit, and with the whole surface of one wall engaging a supporting wall or the like, and a casing 65 fitting said base in either of its positions and providing a removable closure therefor with either of the walls of the base part disposed in a vertical plane in complete engagement with a supporting wall.

70 2. A weather-proof outlet, comprising a base having two side walls joined at right angles to each other, one of said walls having a centrally disposed perforation to receive a conduit, end members, joining the side walls, at a distance from the ends of said side walls, to provide in conjunction with said side walls, rectangular seats for a cover, and a cover having walls, the edges of which register with the edges of the walls of 80 the base and also having end walls covering the ends of the walls of the base, said end walls of the cover having seat members fitting the rectangular seats of the base, said cover fitting and inclosing the base when 85 the latter is secured either to a horizontally or vertically disposed conduit, and wire outlets in said cover.

90 3. A weather-proof outlet having a base-part provided with two co-extensive side walls joined at right angles, one of said side walls having a central perforation to receive a conduit, when either of the side walls is secured to a wall or like support, end members joining said walls at a distance from 95 their ends, and forming, in conjunction therewith rectangular seats for an inclosing cover, a clamp arranged in said base about the perforation and adapted to clamp the base to a conduit, an inclosing casing for the 100 base having wire outlets and forming a complete closure for the base, said casing having walls with edges co-extensive with and registering with the edges of the walls of the base and having end parts fitting the 105 rectangular seats of the base and extending over the ends of the walls of the base, said casing and base being reversible end for end with reference to each other whereby the device may be applied to horizontal or vertical conduits and the wire outlets of the cover in either case may be arranged in line with 110 or at right angles to the line of the conduit.

LOUIS FORT.
